UNITED STATES PATENT OFFICE.

JOSEPH U. MEISTRELL, OF BROOKLYN, NEW YORK.

TYPE-BAR-MACHINE ATTACHMENT.

1,157,243.

Specification of Letters Patent. Patented Oct. 19, 1915.

Application filed May 3, 1915. Serial No. 25,468.

To all whom it may concern:

Be it known that I, JOSEPH U. MEISTRELL, a citizen of the United States, and resident of Brooklyn, in the county of Kings and State of New York, have invented certain new and useful Improvements in Type-Bar-Machine Attachments, of which the following is a specification.

This invention relates to type-bar making machines and more especially to attachments for planing the type bars or slugs as they are deposited in the galley, the object of the device being to so arrange the bars that as they pass along the galley the type faces will not be damaged by contact with it or rubbing the face of the type along the side of the galley, as frequently occurs, if not properly arranged in the galley. These and other objects and details of the invention are more fully explained in the following specification, set forth in the claims and illustrated in the drawings, in which:

Figure 1. is a side elevation of a part of a type bar making machine showing the elevator, the galley and the planing mechanism. Fig. 2. is an enlarged view of the planing tappet. Fig. 3. is a side view of the same. Fig. 4. is a similar side view with the tappet in its inoperative position. Fig. 5. is a detail view of one of the fingers of the tappet. Fig. 6. is a modified form of tappet with the elevator raised. Fig. 7. is a similar view with the elevator lowered. Fig. 8. is a side view of Fig. 6.

As the type bars are cast and delivered into the galley 10 they are pushed forward by the lever 11 but no provision has heretofore been made to properly arrange the bars on their ends and they are consequently apt to lean outward or stand irregularly so that the type face 12 is liable to come in contact with the front part of the galley and be injured by the friction resulting from their movement. The object of this invention is to so arrange the type bars in the galley that this danger is obviated, and to retain the bars in the galley when the vise on the front of the machine is lowered. On the frame of the machine and adjacent to the elevator 13, a bracket 14 is secured which carries at its upper end 15 a pin 16 on one end of which is the tappet arm 17 having its upper end padded with some soft material 18, such as leather or rubber and extending high enough to strike the type faces at certain intervals. The upper end of the arm

extends laterally so as to engage a number of the type-bars.

Journaled on the pin 16 at the outer side of the arm 17 is a finger 19 whose movement in one direction is limited by a pin 20 projecting from the side of the arm and consequently shifts its position as the arm is swung on its pivot. The bracket 14 also carries a similar pin 21 and secured on these two pins are the ends of a spring 22 under tension and adapted to retain the pin 20 and the arm 17 on one or the other side of the pin 16 as shown in Figs. 3 and 4. In one of these positions the arm 17 is against the type bars while the arm is held in its horizontal position by the pins 23' and 24' and in both instances by the tension of the spring 22.

Loosely journaled on the pin 16 is a finger 23 which has its hub 24 reduced at 25, to form a shoulder 26 to normally abut a similar shoulder 26' on the finger 19. The finger 23 is connected with and operates the arm 17 in its downward movement by means of a pin 23'' which engages a stop 17' on the hub of the arm, but the finger is nevertheless capable of a reverse movement and the disengagement of the shoulders 26 and 26' and the pin 23'' with its stop 17'. The two fingers 19 and 23 are normally held at about ninety degrees from each other by a flat spring 27, one end of which is secured to each finger so as to give an outward tension and cause the shoulders to engage, but the spring allows them to close toward each other. It will thus be seen that the two fingers and the arm are adapted to assume vertical and horizontal positions while the fingers are capable of yielding toward each other.

The above described tappet is operated by a lateral pin 28 projecting from the elevator and shown in dotted lines in Figs. 3 and 4 with arrows to denote the direction of movement to operate the fingers. Fig. 3 shows the tappet arm raised against the type bars and the pin 28 descending and about to throw it to the position shown in Fig. 4 so the type bars may be advanced. In the latter view the pin 28 is ascending and is about to throw the arm 17 against the type-bars to push them from the front of the galley 10 and to a uniform plane.

In case that from inadvertence the tappet arm is at any time misplaced and occupies its wrong position with relation to the pin

28, the latter will strike the fingers from the wrong side and on account of the yielding nature of the fingers, throw them aside without operating the arm. If in Fig. 3 5 the pin 28 approaches the finger 23 from below the spring 27 yields but returns the finger to its horizontal position after the pin passes on and leaves it in position to be acted on as the pin passes down. The 10 action on the finger 19 in Fig. 4 is the same and if the pin 28 acts upon the finger from its upper side, the finger yields but is caused to return to its normal position by the 15 spring 27.

15 The modified form shown in Figs. 6, 7 and 8 consists of a tappet arm 30 having a lateral extension 31 which carries rollers 32 and 33 to travel on the cam rod 34 attached to the elevator and provide a movement to cause the padded end 18 of the tappet to 20 extend toward the end of the slug column and deliver a blow to their faces to plane them. The arm 30 is universally mounted on a fork 36 by means of the hinge 35 and the pivot 37 while the spring 38 tends to 25 keep the rollers 32 and 33 in contact with the cam rod 34, the roller 32 providing for an in and out movement while the roller 33 swings the arm on the pivot 37. A spring 39 is employed to carry the arm inward.

30 As the elevator ascends, the tappet is moved away from the type face but as it reaches its lower position, the tappet is permitted to hit the type bars with its padded 35 end, so that the bars are driven back to a uniform position.

35 As the tappet arm is carried past the center in the upward movement, the strength of the spring is sufficient to cause the tappet 40 arm to strike the type bars a quick and sharp blow to drive them in place. On account of their heated condition the bars often adhere to each other and this blow separates them.

45 It is very often necessary to lower the vise and open the front of the galley to allow corrections and inspection of the bars. In this case the tappet arm may remain in 50 its elevated position and will retain the bars in the galley and prevent them falling out.

55 It is obvious that other similar forms of tappets conveniently located may be operated by moving parts of the machine and yet be included in the scope of the appended claims.

What I claim is:

1. In an attachment for type bar making machines, the combination with a tappet adapted to strike the type bars on their faces 60 and plane them as they are delivered, of means connected with a moving part of the machine to operate the tappet.

2. In an attachment for type bar making machines, the combination with a tappet 65 hinged to the frame of the machine and in

front of the type bar faces and adapted to strike them, of adjacent moving means to operate the tappet.

3. In an attachment for type bar making machines, the combination with a tappet 70 hinged in front of the galley of the machine and adapted to engage the faces of the type bars, of a projection connected with a moving part of the machine to operate the tappet on the face of the type. 75

4. In an attachment for type bar making machines, the combination with a bracket secured to the machine adjacent to the galley, of a tappet pivoted in the bracket and at the front of the galley, and means carried by a moving part of the machine for operating the tappet to plane the type bar faces while in the galley. 80

5. In an attachment for type bar making machines, the combination with a tappet 85 arm pivoted on the machine frame in front of the galley, a pivot, yielding fingers on the pivot and connected with the arm, and a moving stud to operate on one side of the fingers and swing the tappet. 90

6. In an attachment for type bar making machines, the combination with a bracket secured to the machine, of a tappet arm pivoted in the bracket, a pivot pin, yielding fingers on the pivot pin connected with the 95 tappet arm, an elevator, and a stud from the elevator and adapted to engage the fingers and turn them alternately on their pivot.

7. In an attachment for type bar making 100 machines, the combination with the frame of the machine, of a bracket, a pivot pin in the bracket, a tappet arm on the pivot pin, a yielding finger on the pivot pin and resting on a stop on the arm, a second finger 105 on the pin and connected with the arm and adapted to yield toward the first finger, a spring adapted to separate the fingers, a spring connecting the arm with the bracket and adapted to hold it on either side of the 110 pivot center, an elevator, and a stud on the elevator and adapted to turn the arm and fingers on the pivot.

8. In an attachment for type bar making machines, the combination with the frame, 115 of a bracket, a tappet arm pivoted in the bracket, a finger pivoted adjacent to the arm, a stop limiting the movement of the arm in one direction, a stop for one side of the finger, a second finger, a stop on the arm and 120 connecting it to move with the second finger in one direction, means permitting a reverse movement of the fingers, an elevator, and a stud on the elevator to throw the fingers and arm to a vertical or a horizontal 125 position or vice versa.

9. In an attachment for type bar making machines, the combination with a frame, of an intermittently moving elevator, a stud on the elevator, a tappet adjacent to the eleva- 130

tor, a galley containing the type bars, and means connected with the tappet and operated by the elevator to cause the former to deliver a blow on the face of the type bars to plane them.

10. In type-bar machines, the combination with the frame thereof, of means for engaging the faces of the type bars after they are delivered and planing them, and means connected with a moving part of the machine for operating the face engaging means.

11. In a type-bar machine, the combination with the frame thereof, of intermit-

tently moving means for engaging the faces of the type bars when they are delivered into the galley of the machine and planing them, and means connected with a moving part of the machine for operating the intermittently moving means.

Signed at New York in the county of 20
New York this 22d day of April A. D. 1915.
